UNITED STATES PATENT OFFICE.

HARRY M. PFLAGER, OF ST. LOUIS, MISSOURI, ASSIGNOR TO DOUBLE BODY BOLSTER COMPANY, OF ST. LOUIS, MISSOURI, A CORPORATION OF NEW JERSEY.

SIDE-SILL BRACKET.

1,047,834.

Specification of Letters Patent. Patented Dec. 17, 1912.

Application filed April 9, 1912. Serial No. 689,571.

To all whom it may concern:

Be it known that I, HARRY M. PFLAGER, a citizen of the United States, residing at St. Louis, Missouri, have invented a certain new and useful Improvement in Side-Sill Brackets, of which the following is a full, clear, and exact description, such as will enable others skilled in the art to which it appertains to make and use the same, reference being had to the accompanying drawings, forming part of this specification, in which—

Figure 1 is a side elevation of a side sill bracket of my improved construction. Fig. 15 2 is a front elevational view of the bracket. Fig. 3 is a top plan view of the bracket with parts of the car underframe shown in dotted lines. Fig. 4 is a side elevation of a modified form of the bracket. Fig. 5 is a plan view of the form of bracket seen in Fig. 4. Fig. 6 is a front elevation of the modified form of the bracket shown in Figs. 4 and 5. Fig. 7 is a side elevation of a further modified form of the bracket. Fig. 8 is a plan view of the form of bracket seen in Fig. 7 and Fig. 9 is a front elevational view of the form of bracket illustrated in Figs. 7 and 8.

This invention relates generally to car construction and more particularly to a reinforcing and strengthening bracket utilized at the lower corners of the car body in connection with the underframe and the end frames.

In order to overcome the tendency of car bodies to telescope during collisions various structures have been devised and are at present in general use, which structures include cast metal underframes, one-piece end frames and combined double body bolsters and platforms. To further strengthen and reinforce the ends of car bodies so as to reduce to a minimum the tendency of said bodies to telescope during collisions I propose to provide strengthening and reinforcing members in the form of angle brackets that are applied to the side sills of the underframe and to attach to said angle brackets the lower side portions of the end frames.

My improved cast metal brackets are particularly designed for use in connection with cast metal underframes and one-piece end frames of the type disclosed in Patents #917,716 dated April 6, 1909 and #929,705

dated August 3, 1909 although it will be readily understood that the bracket can be advantageously employed in connection with built-up underframes and end frames.

The principal object of my invention is to provide a simple, strong and rigid one-piece cast structure which can be readily applied to the existing types of underframes and end frames and which will provide a solid substantial brace for the lower portion of the end frame, and which brace will effectually resist severe end shocks and crushing stresses due to collisions and oppose all tendency of the cars to telescope, thereby affording maximum degree of safety to life and property.

Referring by numerals to the construction illustrated in Figs. 1, 2 and 3, 10 designates the side sill of the underframe, 11 the end sill of said end frame and 12 the one-piece end frame. My improved bracket as shown 75 comprises a plate 13 which is generally triangular in shape when viewed in side elevation and formed integral with the edges of this plate is an outwardly projecting marginal flange 14. Formed integral with and 80 projecting inwardly from the heel or rear lower portion of the plate 13 is a horizontally disposed lug 15, which, when the bracket is applied to the underframe, bears directly against a shoulder 16 formed on top 85 of the side sill of the underframe. The bracket is rigidly fixed to the side sill of the underframe by means of rivets or like fastening devices 17 which pass through the lower portion of the plate 13 and the corresponding portion of the side sill 10. When 90 properly applied for use the base of the bracket rests directly upon a horizontally disposed flange 10^a which projects outwardly 95 from the lower portion of the side sill 10. The lower portion of the side member of the end frame 12 bears directly against the front side of the bracket and these engaging parts are rigidly fixed to one another by means of rivets or in any suitable manner.

In the modified construction illustrated in Figs. 4, 5 and 6 the base of the bracket is cut away along its lower outer edge, as designated by 18 in order to accommodate the horizontally disposed flange of an angle side sill 19, and which construction is utilized where combined double body bolster and platform castings form a part of the underframe and are united by continuous flanged side sills such as 19.

In the modified construction illustrated in Figs. 7, 8 and 9 the marginal flange 14 is dispensed with at the base of the bracket and said base terminates a slight distance 5 above the flange 10^a of the underframe in order to accommodate an angle side sill 20 having an extra wide base flange. In this construction the inwardly projecting bracket extends entirely across the lower portion of 10 the bracket, as designated by 15^a and this bracket bears directly upon and is rigidly fixed to the corresponding portion of the underframe. In this form of device integral strengthening webs 15^b extend from the ends 15 of the bracket or flange 15^a upwardly along the front and rear edges of the main body portion of the bracket.

My improved reinforcing and strengthening bracket is preferably cast in a single 20 piece so that it can be readily applied for use, and when properly combined with an underframe and end frame provides a very strong and comparatively light construction which unites with the end frame and resisting 25 all end shocks and crushing stresses, thereby minimizing the tendency of telescoping of the cars due to collisions when said cars are running at high speed.

By the use of reinforcing brackets of my 30 improved construction the tendency of the upper portion of an end frame to swing inwardly under crushing strains is resisted and the brackets themselves are rigidly supported upon the underframe by the engagement of the rear portions of the flanges or 35 brackets 15 against the shoulders 16.

The bearing of the bracket or flange 15 directly on top of the side sill of the end frame and against the shoulder 16 removes 40 all shearing strain from the rivets utilized in fastening the bracket to the underframe.

My improved brackets, while particularly 45 designed for use in connection with cast metal underframes and cast metal end frames, can be advantageously employed in connection with built-up structures, and when combined with either integral or built-up structures provides a very strong, rigid construction which is anti-telescopic in effect 50 for the reason that it effectually braces the lower side portions of the end framing against end shocks and crushing stresses.

It will be readily understood that minor 55 changes in the size, form and construction of the various parts of my improved structure can be made and substituted for those herein shown and described without departing from the spirit of my invention, the scope of which is set forth in the appended 60 claims.

I claim:

1. The combination with a car underframe having shoulders on its side sills and a car end frame, of brackets positioned between 65 the lower side portions of the end frame and

the shoulders on the side sills of the underframe.

2. The combination with a car underframe provided with shoulders on its side sills and a car end frame, of brackets positioned between the lower side portions of the end frame and the shoulders on the side sills and means for rigidly fixing said brackets to the underframe and end frame. 70

3. The combination with a car underframe 75 and end frame, of brackets positioned between the lower side portions of the end frame and said underframe and the heel portions of which brackets bear against shoulders on the underframe. 80

4. The combination with a car underframe and end frame, of brackets positioned between the lower side portions of the end frame and said underframe, the heel portions of which brackets bear against shoulders on the underframe and means for rigidly fixing said brackets to the underframe and end frame. 85

5. The combination with a car underframe 90 and end frame, of brackets positioned between the lower side portions of the end frame and the underframe, parts of which brackets bear against shoulders formed on the side sills of the underframe. 95

6. The combination with a car underframe and end frame, of brackets positioned between the lower side portions of the end frame and the underframe, parts of which brackets bear on top of the side sills of the underframe and the heel portions of which 100 brackets bear against shoulders on the underframe.

7. The combination with a car underframe and end frame, of brackets positioned between the lower side portions of the end frame and underframe and flanges projecting inwardly from said brackets, which flanges bear against shoulders formed on top of the side sills of the underframe. 105

8. The combination with a car underframe 110 and end frame, of brackets positioned between the lower side portions of the end frame and underframe and flanges projecting inwardly from said brackets, which flanges bear on top of the side sills of the 115 underframe and the heel portions of which flanges bear against shoulders on the underframe.

9. The herein-described car end frame reinforcing bracket comprising a plate 120 adapted to engage the side sill of an underframe and the lower side portion of an end frame and a lug on the heel portion of said bracket, which lug overlies a portion of the underframe and bears directly against a 125 shoulder on the side sill of said underframe.

10. The herein-described reinforcing bracket for the end frames of car bodies comprising a plate having a marginal flange, 130 which plate is adapted to be applied to the

end sill of a car underframe and a lug on the heel portion of which plate for engaging a shoulder on the side sill of the underframe.

5 11. The herein-described reinforcing bracket for car end frames comprising a plate, means for rigidly fixing said plate to the side sill of an underframe and a horizontally disposed flange projecting inwardly from said plate for engagement with the top of the underframe and with a shoulder formed on said underframe.

10 12. The herein-described reinforcing bracket for car end frames comprising a

plate, a horizontally disposed flange projecting inwardly from said plate for engagement with the top of the underframe and with a shoulder on said underframe and a vertically disposed flange on the front side of the plate for engagement with the end frame.

In testimony whereof I hereunto affix my signature in the presence of two witnesses, this 2nd day of April, 1912.

HARRY M. PFLAGER.
